UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

MACHINE FOR SETTING EDGES.

1,360,990.

Specification of Letters Patent. Patented Nov. 30, 1920.

Application filed November 12, 1917. Serial No. 201,523.

To all whom it may concern:

Be it known that I, OTIS R. ANGELL, a citizen of the United States, residing at Haverhill, in the county of Essex and State of Massachusetts, have invented certain new and useful Improvements in Machines for Setting Edges, of which the following is a specification, reference being had therein to the accompanying drawings.

This invention relates to machines for setting and burnishing the edges of shoe soles and more particularly to means for supporting and for reciprocating the operating tool.

In machines of the above type as at present constructed and in which cranks or eccentrics have been employed for reciprocating the tools, much annoyance has been caused by reason of the excessive vibration produced, resulting in disagreeable noise and rapid wear of parts. It is an object of the present invention to so construct a machine of the above type as to eliminate all unnecessary machine parts and at the same time to reduce undesirable vibration to a minimum.

It is a further object of the invention to provide in an edge setting machine a tool holder constructed to simultaneously hold a plurality of tools and adapted to be so controlled as to present either of said tools in working position at the will of the operator.

Other and additional objects and advantages of the present invention together with desirable details of construction and improved combination of parts will be herein-after described and particularly pointed out in the claims.

Figure 1 is a side elevation showing the essential elements relating to the tool-operating mechanism, certain parts being broken away to show the internal structure. Fig. 2 is an end elevation of the same, with parts broken away. Fig. 3 is a top plan view and Fig. 4 is a diagrammatic elevational view illustrating the operative mechanism as mounted in position on the machine frame.

1 indicates a hollow shaft which may be suitably supported in bearings upon the frame of the machine, suitable means being provided as herein shown for continuously rotating said shaft. Such means may comprise a pulley 1^x and a driving belt, or any

of the well known equivalents therefor. Within said hollow shaft 1 is located a relatively fixed shaft, support, or rod 2. Any desirable means as herein illustrated may be provided for holding said shaft in either of two positions, 180 degrees apart, and for turning said shaft from one of said positions to the other. This means may comprise a gear 3^b fixed to the shaft 2, and suitable devices for turning and locking said gear, such devices as herein shown for example comprising a rack segment fast on a shaft 50 and meshing with the gear 3^b and a locking and turning handle lever fast to the other end of the shaft, but no claims are made herein to this part of the mechanism, and any other equivalent means may be substituted therefor.

The outer end of the supporting shaft 2 is provided with an enlargement 4, said enlargement being slotted or bifurcated to form two opposed spaced apart arms 5 and 6. Passing through alined bearing openings in said arms is a pintle pin or shaft 7, said shaft being provided upon one end with a head 8 and being screw-threaded upon the other end at 9 to engage with the screw threads of a nut 60. Mounted to rock about said pin 7 between the arms 5 and 6, and in the vertical plane of the shaft 1, is a tool-carrying head 10, said head being provided with upwardly and downwardly extending portions 11 and 12, the extremities of said portions 11 and 12 being provided with members 13 and 14 adapted to have mounted thereon the usual tool holders employed in this type of machine.

The head 10 is slotted in its central plane, as shown at 15, said slotted portion extending into the parts 11 and 12 respectively. Within the extremities of the slot in said head are mounted a pair of rollers 16 and 17, said rollers being mounted to turn in said slot by means of pins 18 and 19 passing through the side portions of the head, and secured therein in any suitable manner. The rollers 16 and 17, as will be noted by inspection of Figs. 2 and 3, are provided with central grooves 20, the purpose of which will be hereinafter noted.

As shown at 21 the shaft 1 is provided at its end with a cam or eccentric pin and engaging said pin or cam by means of a suitable journal opening is a block 22, said block being grooved at its upper and lower

edges as shown at 23. 24 is a yoke-member having a central opening 25 encircling the shaft 1, said yoke-member, however, being free to move both up and down and laterally with respect to the shaft. The yoke 24 is provided with tongues 26 adapted to slide within the grooves 23 of the block 20, and is further provided upon the outer end of its arms with cam surfaces 27, 28, said surfaces being arranged for contact with the rollers 16 and 17 respectively. Projecting centrally of cam-members 27 and 28 are a pair of fins 29, 30, said fins being arranged to project within the grooves of the rollers.

The operation of the machine is as follows: With the support 2 held in fixed position, the head 10 being thereby retained in a vertical plane, rotation of shaft 1 will cause rotation of the cam or pin 21 fixed thereto. As said pin has bearing engagement with the journal opening in block 22, said block will be forced to assume a rotary movement with respect to a fixed point upon the frame of the machine. As the yoke-member 24 is in engagement with said block, said yoke-member tends to partake of the movement of the block, but by reason of the construction shown, however, including the slidable engagement of said block and yoke, the vertical components only of the movement of said block are effective in moving the yoke 24, horizontal components of such movement being of no effect upon the yoke due to the horizontal sliding of block within the yoke. As the cam surfaces 27 and 28 are in contact with the rollers 16 and 17, the vertical movement of the yoke, through the cam action of said parts, will cause the head 10 to rock about its pivotal support 7, thus producing a desired action of the operating tools. As will be noted from the construction described, the block and yoke would be free to turn with the shaft, and would therefore be ineffective except for the provision of the fins engaging within the grooves of the rollers. As the rollers are held in a fixed vertical plane, by reason of their connection to rod 2, the block and yoke, through the action of said fins, are also held in proper position, and therefore are able to properly perform their intended function.

While in the present disclosure the tool-holding head is shown as adapted for carrying two oppositely disposed tools, and while as above indicated it is the purpose of this invention to employ said tools alternatively as by turning the supporting head 2 into either of two diametrically opposed positions, it is within the scope of this invention to employ a single tool holder upon said head and to provide means to hold said head always in fixed position. While as

herein disclosed, and as is customary in such machines, the tool holders are arranged in a substantially vertical plane, it may be noted that by merely changing the fixed position of the shaft or support 2 the tools might be located to operate in any other preferred position, and such change of operative position is contemplated as within the scope of the present invention.

While the above is a preferred embodiment of the invention, it is not to be understood that it is to be limited to the specific details hereinbefore described, but that any or all changes or modifications of structure within the province of mechanical skill are to be regarded as a part thereof so far as they may be embraced within the scope of the annexed claims.

Having thus described the invention what I claim as new, and desire to protect by Letters Patent of the United States, is:

1. In an edge setting machine, a support, a tool-holding head pivoted to rock with respect thereto, a slidable cam, means for moving said cam, and a roll carried by the head and arranged for contact by said cam, whereby movement of the latter serves to rock the head.

2. In a machine of the class described, a support, a tool holder pivoted to rock thereon, a reciprocable cam, means for reciprocating said cam, and an element carried by the head and adapted for contact by said cam whereby reciprocation of the latter serves to rock the head.

3. In an edge setting machine, a normally fixed support, a tool-holding head adapted to hold a plurality of tools and pivotally mounted upon the support, said head being provided with rollers upon opposite sides of its pivotal point, a slidable member having oppositely inclined cam surfaces arranged to contact with the respective rollers, and means for reciprocating said member.

4. In a machine of the class described having a power driven shaft and a pivotally mounted tool-holding head, in combination, an eccentric pin upon the end of said shaft, a block having a journal bearing for said pin and mounted thereon, a yoke-member slidably engaging said block, and arranged to actuate said head, and means for changing the plane of movement of said yoke-member.

5. In an edge setting machine, a support, a tool holder pivoted thereon, a roller mounted upon said tool holder at one side of its pivotal point, said roller having a groove in its periphery, a slidable member having a cam surface for engagement with said roller and a projecting fin arranged to enter the groove in said roller, and means for reciprocating said member.

6. In an edge setting machine having a

5 pivotally mounted tool-holding head, a power driven shaft, an eccentric pin upon the end of said shaft, a block having a bearing opening engaging said pin, a yoke member slidably engaging opposite faces of said block, a pair of oppositely inclined cam-surfaces carried by said yoke and provided with outwardly projecting fins, and a pair of rollers mounted upon said head contacting with the respective cams and having grooves for engagement by said fins, whereby rotation of the shaft serves to rock the tool-holding head.

10 7. In an edge setting machine a slotted support providing opposed bearing openings, a pintle pin or shaft fixed in said openings, a tool-holding head pivoted to rock upon said pin or shaft, a plurality of rolls carried by said tool holder upon diametrically opposite sides of said shaft, a cam member engaging said rolls, and means for actuating said cam-member.

15 8. In an edge setting machine, a support, a driving shaft, a tool-holding head pivoted on said support and in the axis of said shaft, a cam on said shaft, a block engaging said cam, a member slidably engaging said block, and means carried by said member for actuating said head.

20 9. In an edge setting machine, a support, a driving shaft, a tool-holding head pivoted to said support to vibrate in a plane containing the axis of said shaft, a cam on said shaft, a block engaging said cam, and a

25 30 35 member slidably engaging said block and

constructed and arranged to actuate said tool-holding head.

10 10. In an edge setting machine, a rocking tool-holding head, and a reciprocating cam for imparting to said tool holding head 40 its normal operative movement.

11. In an edge setting machine, a rocking tool-holding head, and a sliding cam for imparting to said tool holding head its normal 45 operative movement.

12. In an edge setting machine, a rocking tool-holding head, and a bodily movable cam for imparting to said tool holding head its normal operative movement.

13. In an edge setting machine, in combination, a tool holding head mounted for operative movement in a plane, and a cam member reciprocable in said plane for actuating said tool holding head.

14. In an edge setting machine, in combination, a tool holding element mounted for movement in a plane, arcuate path, and a cam member movable in a substantially rectilinear path for imparting such movement to said element.

15. In a machine for setting edges, a tool holder, a pivoted support for said holder, a cam member for oscillating said holder upon its support, and means for vibrating said cam member in a substantially rectilinear 60 65 path.

In testimony whereof, I have signed my name to this specification.

OTIS R. ANGELL.
